TORQUE WRENCH LEVER

Bosko Grabovac, Mission Viejo, Calif., assignor to
Consolidated Devices, Inc., South El Monte, Calif.

Filed June 24, 1974, Ser. No. 482,332

Term of patent 14 years

Int. Cl. D8—05

U.S. Cl. D8—24

FIG. 1 is an isometric view showing the top, side and rear end of a torque wrench lever embodying my new design;

FIG. 2 is a bottom view of my new design, a portion thereof being removed for use of illustration;

FIG. 3 is a view showing the rear end thereof;

FIG. 4 is a view showing the front end thereof; and

FIG. 5 is an isometric view of my new design with a portion thereof being removed for use of illustration and showing its rear end in an extended position.

I claim:

The ornamental design for a torque wrench lever, as shown and described.
